UNITED STATES PATENT OFFICE.

FREDERICK M. FURBER, OF REVERE, MASSACHUSETTS, ASSIGNOR TO UNITED SHOE MACHINERY COMPANY, OF PATERSON, NEW JERSEY, A CORPORATION OF NEW JERSEY.

BLACKING-MACHINE.

1,195,348.

Specification of Letters Patent. Patented Aug. 22, 1916.

Application filed July 2, 1913. Serial No. 777,112.

To all whom it may concern:

Be it known that I, FREDERICK M. FURBER, a citizen of the United States, residing at Revere, in the county of Suffolk and 5 State of Massachusetts, have invented certain Improvements in Blacking-Machines, of which the following description, in connection with the accompanying drawings, is a specification, like reference characters on 10 the drawings indicating like parts in the several figures.

This invention relates to machines for use in finishing boots and shoes, and particularly to machines for applying blacking, 15 stain, or other finishing material, herein referred to generically as blacking, to the edges of the heels or soles of boots and shoes.

The invention has for its general objects 20 to improve machines of this character with a view particularly to enabling them to produce a better and more uniform quality of work, to meet a greater variety of conditions, and to prevent the staining of parts 25 of the shoe other than the part to which blacking is being applied.

In using machines of this character there 30 is always a tendency for the blacking applying brush to load up with blacking to such an extent that it will apply an excess 35 of blacking to the work. While this condition can be controlled satisfactorily with mechanisms now in use where thin blackings are employed, it is impossible to do 40 satisfactory work with very thick heavy blackings, which many manufacturers prefer to use, for the reason that these materials pack down the bristles of the brush (particularly if a soft bristle brush is used) 45 thus preventing the brush from fitting the heel or sole edge properly and causing it to apply the blacking unevenly to the edge.

It is a particular object of this invention 50 to devise a machine that will operate satisfactorily with the various blackings used in shoe manufacturing. To this end it is proposed to equip the machine with a mechanism for combing the blacking applying brush to prevent the blacking from packing 55 down the bristles in the manner described and to maintain the brush in a proper operative condition.

The invention also provides a novel form 60 of scraping mechanism which is designed 65 to remove surplus blacking from the brush

and to maintain on the brush a substantially uniform quantity of blacking.

Machines of this character usually include a guide adapted to enter the rand crease of the shoe to aid the operator in 60 guiding the shoe relatively to the brush while the brush wipes blacking upon the edge of the shoe bottom. Usually this guide is employed also to apply blacking to the upper surface of the rand. It is desirable 65 to coat thoroughly the exposed surfaces of the rand, but it is very important on many classes of work, particularly on colored goods, to prevent any of the stain with which the heel and rand are coated from 70 touching the upper of the shoe. Even if the blacking operation is performed without soiling the upper, the blacking applying devices may have introduced into the rand crease a surplus of blacking which will be 75 squeezed out of the crease at some later operation, as for instance in the heel seat heading operation, and will then discolor the upper. With a view to meeting these conditions, the present invention provides a 80 novel scraping mechanism for the rand crease guide that enables the workman to control nicely the quantity of blacking that will be applied to the rand.

These and other features of the invention 85 will be clearly understood from the following description and the accompanying drawings, and the novel features will be pointed out in the appended claims.

In the drawings, Figure 1 is a perspective 90 view of a machine embodying the present invention; Fig. 2 is a vertical sectional view of the machine shown in Fig. 1, the section being taken through the applying brush; and Fig. 3 is a plan view, partly in section, 95 showing the relative positions of the applying brush and the parts coöperating therewith.

For convenience in illustration the features of the invention have been shown as 100 embodied in a machine built in accordance with U. S. Letters Patent No. 1,025,523, dated May 7, 1912, but their use is not limited to machines of this construction.

The machine shown comprises a post 2 105 and a head 3 having suitable bearings for a main shaft 5. This shaft has mounted thereon fast and loose pulleys 6 and 7, respectively, and a belt shipper 8 is provided to transfer a belt (not shown) from one 110

pulley to the other to start or stop the machine.

Fast on the forward end of the shaft 5 is a worm gear 9, Fig. 2, that meshes with and drives a gear wheel 11 which is formed integral with the flanged sleeve 12. The blacking applying brush 13 is clamped between the flange 17 of the sleeve 12 and a nut 18 threaded upon the threaded lower end of 10 said sleeve. This sleeve and the brush revolve on a vertical spindle 19 that is removably held in the frame of the machine between two arms, the upper arm being drilled to receive the spindle and the lower 15 arm carrying a pin 20 which is straddled by the lower end of the spindle to hold the spindle against rotation.

The shaft 5 has fast thereon a worm gear 21 that meshes with a gear wheel 22 which 20 is fixed on a shaft 23 lying at right angles to and supported below the shaft 5. This shaft carries a blacking conveying disk 25 that dips into a body of blacking held in a tank 26.

25 A shaft 28 supported parallel to the shaft 23 in a bearing 29 of the frame and geared to the latter shaft carries at its outer end the rotary rand guiding and blacking conveying device 30 which operates, as more 30 fully shown and described in the above mentioned patent, to convey the blacking from the disk 25 to the applying brush 13 and also to apply blacking to the rand crease of the shoe. Scrapers 32 which serve to break 35 up and remove the blacking that may have dried on the outer face of the rand guide 30 are carried by a semi-circular yoke 33 adjustably supported on the frame and are spring pressed into engagement with the 40 outer face of the guide.

An arm 34 pivoted at one end on the pin 35 and extending forwardly over the guide 30 carries on its forward end a tubular holder 36 for a scraper 37 of leather, felt, 45 or suitable material which is notched to straddle the peripheral edge of the guide, this scraper being adjustable with the holder by a screw 38 to compensate for wear. The arm is operated to maintain the scraper in 50 uniform yielding engagement with the guide by resilient or spring rods 39 which are secured in the frame and bear on a projection extending laterally from the forward end of the arm 34.

55 The scraper 37 is shaped to bear both on the surface of the guide 30 that runs in contact with the counter of the shoe, and also on the surface that engages and applies blacking to the rand, most of the pressure, however, coming on the counter engaging surface. The pressure of the springs 39 is applied to the arm 34 in a direction tending to move the scraper toward the axis of rotation of the guide 30 and, consequently, 60 holds the scraper yieldingly in engagement

with both surfaces of the guide that engage the work. The adjustment of the scraper afforded by the screw 38 also is toward the axis of the guide and serves to take up any wear of the scraper. Obviously, this scraper 70 may be shaped to remove more or less of the blacking from the rand engaging face of the guide as the operator may desire. Ordinarily the scrapers 32 will remove all the blacking that it is necessary to take off the 75 rand guide but the additional scraper 37 is intended particularly for use where unusual care must be exercised to prevent staining the counters, as for instance, on colored stocks, or where there is danger of applying 80 too much blacking to the rand crease.

As above stated, the blacking applying brush 13 tends to become heavily loaded with blacking and if a thick blacking is used the bristles mat together and pack down so 85 that the brush does not apply an even coating to the heel. In order to straighten up the bristles of the brush and prevent them from packing together, I provide a comb 40 consisting of a hub having two oppositely 90 disposed rows of teeth 41 curved forwardly to enable them to dig into the body of the brush and pick up the bristles and straighten them out. This comb is secured to a sleeve 42 by a nut 43 and the sleeve 42 is mounted 95 fast on the lower portion of a vertical spindle 45 which is rotatably supported in the frame piece 46. A spiral gear 47 fast on the sleeve 42 meshes with another spiral gear 48 on the main shaft 5 and drives the 100 spindle 45 and the comb 40 in a direction opposite to the direction of rotation of the brush 13. The ratio of the gears 47 and 48 is such that the comb 40 is driven at a much greater speed than the brush 13 so that the 105 two rows of teeth engage the bristles of the brush 13 a number of times during one complete revolution of the brush and their motion tends to carry the bristles forward and straighten them out. I have found by experience that the best results are obtained 110 by curving the teeth of the comb forwardly in the direction of their rotation in the manner shown in the drawings.

In order further to insure the removal of the surplus blacking which otherwise would accumulate on the brush 13, a scraper 49 is mounted rigidly on the comb 40 to rotate therewith. This scraper consists of a thin plate fastened to one face of the hub of the 115 brush 40 and having its free edge curved to conform substantially to the peripheral outline of the applying brush 13. This device, during its rapid rotation, engages intermittently the periphery of the applying brush 120 and supplements the action of the comb in removing the surplus blacking from the brush. The blacking so removed drops back into the tank 26.

Having thus described my invention, what 130

I claim as new and desire to secure, by Letters Patent of the United States is:—

1. In a machine of the class described, the combination of a driven blacking applying brush, means for supplying blacking thereto, and a comb arranged to engage and straighten out the bristles of the applying brush substantially throughout its body portion.
- 10 2. In a machine of the class described, the combination of a driven blacking applying brush, means for supplying blacking thereto, and a driven comb arranged to engage and straighten out the bristles of the applying brush substantially throughout its body portion.
- 15 3. In a machine of the class described, the combination of a rotary blacking applying brush, means for supplying blacking to said brush, and a comb mounted in peripheral engagement with the applying brush and arranged to rotate in an opposite direction to the said brush for straightening out the bristles of the brush.
- 20 4. In a machine of the class described, the combination of a rotary blacking applying brush, means for supplying blacking to said brush, and a comb mounted in peripheral engagement with the applying brush and arranged to rotate in an opposite direction to and at a greater speed than the applying brush for straightening out the bristles of said brush.
- 25 5. In a machine of the class described, the combination of a rotary blacking applying brush, means for supplying blacking thereto, and driven means arranged to comb the blacking applying brush to straighten out the bristles thereof.
- 30 6. In a machine of the class described, the combination of a rotary blacking applying brush, means for supplying blacking thereto, and a rotary comb comprising a hub and a plurality of rows of teeth carried thereby and arranged to project into the body of said brush and to straighten out the bristles of the brush.
- 35 7. In a machine of the class described, the combination of a rotary blacking applying brush and a rotary comb having a plurality of teeth curved forwardly in the direction of its rotation, said comb being arranged to engage and straighten out the bristles of the applying brush.
- 40 8. In a machine of the class described, the combination of a rotary blacking applying brush, means for supplying blacking to said brush, a rotary comb having a plurality of teeth curved forwardly in the direction of its rotation and arranged to project into the body of said brush, and means for rotating said comb in a direction opposite to the direction of rotation of said brush and at a greater peripheral speed than said brush.
- 45 9. In a machine of the class described, the combination of a rotary blacking applying brush, means for supplying blacking thereto, and a rotary comb mounted in peripheral engagement with said brush and comprising a hub and a plurality of rows of teeth arranged to project into the body of said brush, said teeth being curved forwardly in the direction of rotation of said comb, and means for rotating said comb in a direction opposite to the direction of rotation of said brush and at a greater speed than said brush.
- 50 10. In a machine of the class described, the combination of a rotary blacking applying brush, means for supplying blacking to said brush, a rotary comb arranged to engage the bristles of said brush, and means carried by said comb to engage the applying brush and remove the surplus blacking from said brush.
- 55 11. In a machine of the class described, the combination of a rotary blacking applying brush, means for supplying blacking to said brush, and a rotary scraping device mounted to engage intermittently the periphery of said brush and having an edge extending substantially continuously across the brush and operating to remove the surplus blacking therefrom.
- 60 12. In a machine of the class described, the combination of a rotary blacking applying brush, means for supplying blacking to said brush, a scraper mounted to rotate into and out of peripheral contact with said brush and having an edge arranged to extend substantially continuously across the brush for removing surplus blacking therefrom, and means for rotating said scraper in a direction opposite to and at a greater peripheral speed than the applying brush.
- 65 13. In a machine of the class described, the combination of a rotary blacking applying brush, a rotary comb mounted in peripheral engagement with said brush and having a plurality of teeth arranged to enter the body of said brush, and a scraper carried by said comb comprising a plate arranged to engage intermittently the applying brush and remove the surplus blacking therefrom.
- 70 14. In a machine of the class described, the combination of a rotary blacking applying brush, means for supplying blacking to said brush, and a rotary comb mounted in peripheral engagement with said brush, comprising a hub and oppositely projecting rows of teeth arranged to enter the body of said brush, said teeth being curved forwardly in the direction of rotation of said comb, and a scraper mounted on said hub consisting of a plate having an edge shaped to conform substantially to the peripheral outline of said brush, and arranged to engage the periphery of said brush to remove blacking therefrom.
- 75 15. In a machine of the class described,

- the combination of a rotary blacking applying brush, a rotary rand guide having a peripheral edge shaped to enter the rand crease of a shoe to guide the shoe relatively to said brush during the blacking operation, and a scraper shaped and mounted to straddle the edge of said guide to prevent the guide from applying a surplus of blacking to the rand crease of the shoe.
16. In a machine of the class described, the combination of a rotary blacking applying brush, a rotary rand guide having a peripheral edge shaped to enter the rand crease of a shoe to guide the shoe relatively to said brush during the blacking operation, a scraper shaped to straddle the peripheral edge of said guide, and means for yieldingly holding said scraper in contact with said edge and arranged to urge the scraper toward the axis of rotation of said guide.
17. In a machine of the class described, the combination of a rotary blacking applying brush, a rotary rand guide having a peripheral edge shaped to enter the rand crease of a shoe to guide the shoe relatively to said brush during the blacking operation, a scraper shaped and mounted to straddle the
- edge of said guide, and means for adjusting said scraper toward and from said edge in directions transverse to the axis of said guide.
18. In a machine of the class described, the combination of a rotary blacking applying brush, a rotary rand guide having a peripheral edge shaped to enter the rand crease of a shoe to guide the shoe relatively to said brush during the blacking operation, said guide having surfaces in contact with the counter and the upper surface of the rand of the shoe, a scraper of yielding material shaped and mounted to straddle the edge of said guide and to bear on both of said surfaces, a holder supporting said scraper for adjustment toward and from said edge, and means operating yieldingly on said holder to press the scraper into contact with said surfaces.

In testimony whereof I have signed my name to this specification in the presence of two subscribing witnesses.

FREDERICK M. FURBER.
